UNITED STATES PATENT OFFICE.

JAMES H. McELROY, OF MIDDLETOWN, NEW YORK.

FASTENING DEVICE.

SPECIFICATION forming part of Letters Patent No. 595,832, dated December 21, 1897.

Application filed June 17, 1896. Serial No. 595,907. (No model.)

To all whom it may concern:

Be it known that I, JAMES H. McELROY, of Middletown, Orange county, New York, have invented a certain new and useful Improvement 5 in Fastening Devices, of which the following is a specification.

My invention relates to fastening devices, and especially to new and improved means of securing boots or shoes whereby a neat fastening of the two parts of the quarter is obtained.

By my invention also I obviate the unseemly appearance of a shoe due to the wearing off of the enamel on the lacing-eyelets.

15 In the drawings I have illustrated a shoe embodying my invention, in which—

Figure 1 is a side elevation of a shoe constructed according to my invention. Fig. 2 is a detail view of the inside of one quarter 20 of such a shoe, and Fig. 3 is a view in section along line $\alpha\alpha$ of Fig. 2.

Like letters of reference refer to like parts throughout the several views.

Referring to the drawings in detail, A represents the shoe, B the quarter, and C a reinforcing-strip placed on the inside of the quarter along the line of eyelet-holes.

In carrying out my invention I cut out the quarter with a supplemental piece b, adapted 30 to be folded over the reinforcing-strip C, and punch-holes D along the crease formed in the quarter when the same is afterward folded over the reinforcing-piece C. I then secure the reinforcing-piece C to the quarter by a line of stitches c' and punch another series of 35 holes E through the reinforcing-piece and the quarter alongside of and a little distance removed from the holes D already made and insert in said holes E brass eyelets. I then fold 40 over the quarter and reinforcing-piece so that the holes D are on the crease or corner thus formed, and then secure the reinforcing-piece and the folded-over portion of the quarter on the inside thereof by a line of stitches c'.

When the parts are in this position, it will be 45 seen that the holes E on the inside of the quarter communicate with the holes D, which pass through only the leather constituting the quarter and thus afford a passage for the lace, which shows no brass eyelets on the outside 50 of the shoe.

Although I have shown my invention as applied to a boot or shoe, I do not wish to limit myself thereto, as it will be obvious that the same may be used in connection with other 55 articles of wearing-apparel.

What I claim as new is—

1. A fastening device comprising the folded-over edge having a series of holes in its outer portions and a corresponding series of eyelet-holes in its folded-over portion in rear of said series of holes whereby said eyelet-holes are invisible from the exterior of the article, but communicate with the holes in the outer portion thereof, substantially as described. 65

2. A fastening device comprising the folded-over edge having a series of holes formed at the bend of the fold and a corresponding series of eyelet-holes in the folded-over portion, said eyelet-holes being invisible from the exterior of the fabric but communicating with the holes at the bend, substantially as described. 70

3. In a boot or shoe, the quarter folded over and secured to a reinforcing-piece, a series of 75 eyelet-holes passing through the reinforcing-piece and folded-over portion of the quarter and a corresponding series of holes formed only in the quarter at the bend thereof, substantially as specified. 80

In testimony whereof I have signed my name to this specification in the presence of two subscribing witnesses.

JAMES H. McELROY.
